(57) **CLAIM**

The ornamental design for a mouse pad for computer, as shown and described.

DESCRIPTION

FIG. 1 is a front, right side, perspective view of a mouse pad for computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an exploded view showing the state in which the upper part of the mouse pad is separated.

The broken lines indicate portions of the article that form no part of the claimed design.

1 Claim, 8 Drawing Sheets
